UNITED STATES PATENT OFFICE

137,504

DESIGN FOR A WOVEN TEXTILE FABRIC

John L. Walther, New York, N. Y.

Application December 9, 1943, Serial No. 111,968

Term of patent 3½ years

(Cl. 92—1)

To all whom it may concern:

Be it known that I, John L. Walther, a citizen of the United States of America, residing in New York city, county of New York, and State of New York, have invented a new, original, and ornamental Design for a Woven Textile Fabric, of which the following is a specification, reference being had to the accompanying drawing, forming part thereof.

The figure on the drawing is a plan view of a woven textile fabric showing my new design.

My design is characterized by the combination of a specific narrow, mottled, lustrous stripe of contrasting color and the particular herringbone pattern disclosed. Each of said stripes divides a single herringbone stripe from an equal width stripe composed of two herringbone stripes.

I claim:

The ornamental design for a woven textile fabric, substantially as shown and described.

JOHN L. WALther.
